UNITED STATES PATENT OFFICE.

ELIEL L. SHARPNECK, OF WINTHROP, MASSACHUSETTS, ASSIGNOR TO S. M. P. WOOD
HEEL COMPANY, A CORPORATION OF MASSACHUSETTS.

HEEL FOR BOOTS AND SHOES.

1,270,449.

Specification of Letters Patent. Patented June 25, 1918.

Application filed December 4, 1916. Serial No. 134,875.

To all whom it may concern:

Be it known that I, ELIEL L. SHARPNECK, a citizen of the United States, residing at Winthrop, in the county of Suffolk and State of Massachusetts, have invented an Improved Heel for Boots or Shoes, of which the following is a specification, reference being had to the accompanying drawings, forming part thereof.

10 This invention has reference to improvements in heels for boots and shoes and particularly to such heels when constructed in part of wood.

One object of the invention is to so construct a heel for boots or shoes whereby the perimeter of the heel may be exposed while the top and bottom edges of said heel, either or both, may be confined and protected.

Another object of the invention is to provide a heel for boots or shoes in which minor imperfections at the edges may be hidden from view.

Other objects of the invention will appear from the following description.

25 The invention consists in the improved heel as will hereinafter be more fully described and pointed out in the claims.

Figure 1, represents a side view of the improved heel.

30 Fig. 2, represents a view looking toward the front of the heel.

Fig. 3, represents a sectional view taken on line 3—3 Fig. 1.

Similar characters of reference designate 35 corresponding parts throughout.

As shown in the drawings and without thereby limiting the invention in its broader aspects the invention is shown, in its preferred specific embodiment, as applied to the heel 5 of a shape often employed in the manufacture of ladies shoes and, from its shape, particularly adapted to emphasize some of the advantages of this improvement. Heels of a shape approximating that shown 40 in the drawings and indicated by reference numeral 5 are or may be constructed from wood, wood or leather pulp and other suitable material shaped to the required pattern by cutting or molding or by some other 45 well known method to produce a heel of graceful design.

In the production of heels of such graceful design the perimetral curves of the heel usually terminate at junctures with re-

versely curved or flat surfaces and, perforce, the lines of juncture of these parts are often quite sharp. In the heel shown the perimetral curves or curved surfaces *a* and *b* meet the reversely curved seat or concavity *c* at such a line of juncture that the comparatively sharp edge *d* is produced and it often happens that at some stage in the process of manufacture this edge *d* is chipped or slightly broken. It is also found that, at and after the attachment of the heel 65 to a shoe, the edge *d* is not sufficiently strong to resist the spreading pressure brought thereagainst and hence the edge *d* is quite often split or broken by such pressure. The fault of splitting or nicking at the juncture 70 between the perimetral curves *a* and the flat lower end *e* of said heel 5 is also obvious.

One of the important objects of this invention is to confine and protect the comparatively sharp lines or shoulders of juncture between the curves *a* and *c* and also between the curves *a* and the flat surface *e* and also to improve the appearance of the heel.

In carrying this invention into practice I 80 construct or provide a heel 5 of leather, wood or of any well known material and, in its preferred form, having a shape substantially as shown with the perimetral curves *a*, *b* meeting the concavity *c* at the upper part of said heel and meeting the flat surface *e* at the lower end of said heel. The concavity *c* may be more or less than that shown and will depend largely upon the shape of the heel seat of the shoe to which 90 the heel is intended to be applied.

At the upper portion of the heel 5 and conformed to the concavity *c* is mounted the thin metal plate or member 6 secured in position in part by its edge or margin 7 which 95 is rolled over the shoulder *d* of heel 5 as shown and covers and confines said shoulder *d* following the curve of said shoulder around the sides and rear of the heel. The central portion of plate 6 preferably is secured to the heel 5 by means of the nails or tacks 8, 8 driven through the plate 6 and into the body of the heel and acting to draw and hold the center of said plate 6 into conformation with said concavity *c*. 105

Plate or member 9 fits against the flat lower end of heel 5 and has the lip or margin 10, 11, turned upward and inward re-

spectively over the line of juncture between the curved surface *a* and said flat surface *e* and between the latter and the curve *b*. This plate 9 is also further secured in place by 5 the tacks 12, 12 driven through said plate 9 into the body of the heel. It is also usual to secure a leather or other well known heel lift *L* in position as indicated in Fig. 1.

The plates 6 and 9 are of metal or material 10 of a color or colors preferably in contrast to the color of heel 5 and add to the artistic appearance of the heel. The margin 7 of plate 6 covers any slight imperfections in the shoulder *d* and confines this shoulder to 15 resist the splitting of the same. Margin 10, 11 of plate 9 covers slight imperfections in the lower edge of heel 5 and resists the splitting of the edge portions.

Having thus described my invention I 20 claim as new and desire to secure by Letters Patent.

1. A heel for boots and shoes comprising a heel body having at its upper end a member having a marginal lip extending down- 25 ward over the perimeter of the heel body, confining the upper edge of said body and

terminating at the perimetric surface of said body close to said edge.

2. A heel for boots and shoes comprising a heel body having at its upper end a concave 30 metal plate having its margin extending outward beyond the edge of the heel body and downward and inward confining said edge.

3. A heel for boots and shoes comprising a heel body having at its upper end a concavity embraced by a thin edge of said heel body, and a thin metal plate member fitting 35 said concavity and having its margin extending outward beyond and inward confining said thin edge of the heel body and having its edge bearing against the perimetric surface of said body.

4. A heel for boots and shoes comprising a heel body having at its upper end a plate 40 extending outward beyond the heel body and having its margin turned inward to confine an edge portion of said body, and a second plate located against the lower end of said heel body and having its margin turned up outside said body, the margins of said re- 45 spective plates spaced apart.

ELIEL L. SHARPNECK.
